UNITED STATES PATENT OFFICE.

CHARLES GILBERT HAWLEY, OF CHICAGO, ILLINOIS.

STEAM-BOILER HEADER.

Application filed March 10, 1924. Serial No. 698,213.

This invention relates to flat stayed headers for steam generators, and has for its object the provision of an improved header of simple form, which can be made to any desired length by use of standard components. It is common practice to construct flat stayed headers by nesting one flanged sheet metal element of dish or basin form within another similar element, and uniting the flanged parts thereof in a convenient manner, and when placing the header in situ, arranging for the joints to be remote from the fire.

The present invention broadly consists in a header for a steam generator comprising two nested channel members having their webs parallel, and their flanges secured together, and end enclosures therefor.

The invention also consists in the improved headers for steam generators substantially as hereinafter described with reference to the accompanying drawings, and defined in the claims.

The invention will be readily understood on reference to the drawings which form parts of this specification. Therein, Fig. 1 represents the outer face of a steam boiler header embodying this invention;—Fig. 2 is a longitudinal section thereof, on the line 2—2 of Fig. 1, viewed in the direction of the arrows;—Fig. 3 is a cross-section on the line 3—3 of Figs. 1 and 2 viewed in the direction of the arrows and also illustrates the method of interconnecting adjacent headers;—Fig. 4 is a partial longitudinal section on the line 4—4 of Fig. 2;—Fig. 5 is a sectional view corresponding to the lower part of Fig. 2 but showing the outside member of the header extended, to provide an anchorage for a cross bar that may be used to fasten several headers together;—Fig. 6 resembles Fig. 3; but illustrates a slightly modified form of the outer member of the header and shows how the water tubes and the stay bolts are installed in the header;—Fig. 7 depicts the fire face of the header, with tubes and stay bolts as employed in one of my steeped radiant heat steam boilers, to which reference may be made in my companion application S. N. 698,728 of even date herewith;—Fig. 8 is a side or edge elevation of the header of Fig. 7;—Fig. 9 is an outer face elevation thereof;—Fig. 10 is a vertical section on the line 10—10 of Fig. 9;—and, Fig. 11 comprises an end view of

one header and cross sections of other headers, placed side by side.

The chief members of this improved steam boiler header comprise the four members, A, B, C, and D. The member A is a deep channel, made of boiler fire box plate. The member B is a shallow channel, preferably of the same material, though metal of lower grade may be used therefor. The web portions A' and B' of these members are flat and they are parallel. The members C and D are end plugs, which close the steam-and-water space E between the two channel members. The flanges B² of the shallow channel B are nested between the flanges A² of the deep channel A and the two members are fastened together by the rows of rivets, F, which are pinch-riveted through respective pairs of flanges A² and B². The members C and D are preferably cupped or pressed to the form shown and therefore present outstanding flanges (C², D²) that nest between the ends of the channel members. They are secured together by perimetral rows of rivets G. The marginal edges are caulked and thus closed tightly together or may be welded autogenously, as indicated at points H. The web portion of the channel A constitutes tube sheet and the fire face of the header; and, as will be apparent, all of the joints of the header are upon the exterior thereof and hence remote from the fire in the boiler furnace and from the hot gases in the several gas passages of the boiler setting. The inner and outer face or web-portions of the header are connected by numerous short stay bolts I. The number and size of the stay bolts, I, will vary with the pressures at which different headers are to be employed. The arrangement thereof always accords with the size and arrangement of the water tubes (such as J) to be accommodated by the header. The side flanges A² of the deep channel A are bulged outward in their intermediate portions between the webs of the two channels, as shown at points A³. These bulging sides A³—A³ are curved preferably upon radii of a length about the same as the distance between the web portions of the two channels. Thus the need of stay-bolting or otherwise bracing the sides of the header is avoided, the various stresses being thereby properly cared for. The juncture portions A⁴ between the portions A' and A³ are formed

upon radii of minimum length for the sake of strength and to the end that tubes *J* may be placed close to the side of the header.

Obviously each tube *J* is secured in a tube hole in the web or tube sheet portion *A'* of the header. For each tube, the web *B'* of the channel *B* has a hand hole *B³* (see Fig. 9) through which the tube may be worked and cleaned. These holes *B³* are usually 10 large enough to permit a tube to be passed through the same and are closed by hand hole plates (not shown). In cases not requiring the insertion of tubes through the outer face of the header, the access holes 15 therein may be closed by screw plugs, *K*, as shown in Fig. 6.

The channels for these headers can obviously be produced by either rolling or bending operations and therefore in any desired 20 lengths, easily producing headers up to thirty or forty feet long, if necessary, and in widths of two to six feet, or more if desired. By increasing the depth of the flanges of the deeper channel member, the 25 depth or thickness of the header member may also be varied as desired.

The channel *B* of the header is usually a 30 rolled member and therefore presents corners *B⁴* that closely contact the inner sides of the flanges *A²*. This is the better construction. But obviously an ordinary sheet 35 may have its edges bent to form flanges *B⁵* as shown in Fig. 6. No difficulty is experienced at the header ends, for it is an easy matter to close with welding material the odd shaped cracks around the plugs *C, D*.

To facilitate the fastening of the header in any desired position as a part of the boiler and its setting, I provide the end brackets 40 here shown, one for each end of the header. The channel *B* as shown is somewhat longer than the channel *A*, providing an anchorage portion *B⁶* beyond the rivets of the adjacent header plug. To this anchorage is riveted 45 the angle iron *L*, having its ends reinforced

by smaller L shaped brackets *L'* riveted to it and to the outstanding flanges of the header. Where a complete bracket is not required the extended edge or end of the member *B* may receive a plain cross anchor 50 bar *M*, as shown in Fig. 5.

Any desired number of steam outlet or blow-off holes may be provided in the end plugs of the headers as shown at *N* in Fig. 11.

For interconnecting abutting headers I provide any required number of cross thimbles, *O*, first flattening the adjacent parts of the bulging sides *A³* of the headers, as shown in Fig. 3. These thimbles are always 60 accessible through adjacent hand holes in the outer face of the header.

As several modifications of this apparently simple invention will readily suggest themselves to those skilled in the art, it is to be understood that the invention is by no means limited to the specific structures herein shown.

Having thus described my invention I claim as new and desire to secure by Letters Patent:

1. The herein described header comprising, in combination, deep and shallow channels having their flanges nested and riveted together, leaving a steam-and-water space 75 between them, suitably fastened plugs closing the ends of said space, and the shallow channel being extended endwise beyond one or both said plugs to provide anchorage supports for the header.

2. The herein described externally flanged and riveted flat header presenting spaced and stay-bolted inner and outer web portions, and bulging sides that extend outwardly beyond the riveted portions of the 85 header flanges.

In testimony whereof I hereby affix my signature.

CHARLES GILBERT HAWLEY.
